UNITED STATES PATENT OFFICE.

EUGENE T. SPECHT, OF CHICAGO, ILLINOIS, ASSIGNOR OF THIRTEEN-TWENTIETHS TO ERNEST A. EASTMAN, OF SAME PLACE.

SUSPENDERS.

SPECIFICATION forming part of Letters Patent No. 661,676, dated November 13, 1900.

Application filed March 5, 1900. Serial No. 7,286. (No model.)

To all whom it may concern:

Be it known that I, EUGENE T. SPECHT, a citizen of the United States, residing at Chicago, in the county of Cook and State of Illinois, have invented certain new and useful Improvements in Suspenders, of which the following is a specification.

My invention relates to certain new and useful improvements in suspenders of the type shown in Letters Patent No. 638,428, granted to me December 5, 1899, and is designed to render the construction of suspenders of that general type simpler and to make them more durable.

While I have shown my improvements as applied to suspenders of this general type, it will be understood that some details thereof might be employed in connection with suspenders of a different character.

To fully illustrate my invention, reference is had to the accompanying sheet of drawings, in which the same letters of reference are used to designate identical parts in all the figures, and in which—

Figure 1 is an elevation of the complete suspenders; Fig. 2, a detail view, on a larger scale, in section on the line 2 2 of Fig. 1. Fig. 3 is a detail view in section on the line 3 3 of Fig. 2. Fig. 4 is a view in elevation of the connecting-piece at the back with the clamp with which it is provided shown in its open position. Fig. 5 is a rear view of the adjustable buckle on the front ends of the suspenders, with a portion of the strap broken away to illustrate the construction. Fig. 6 is a detail view in section on the line 6 6 of Fig.

Fig. 7 is an enlarged detail view on the line 7 7 of Fig. 1; and Fig. 8 is a detail view corresponding to Fig. 2, but showing a modification.

As in the construction shown in my prior patent, the main strap A consists of a single piece, preferably inelastic, which is folded over a roller in the rear connecting-piece B, while its front ends are provided with the clamps C, secured thereon and having the hooks D, which take over the lower cross-piece in the buckle E, thus forming the loops F for receiving the front tabs G. With this construction, as will be readily seen, the main strap A can slide back and forth over

the roller on the rear connecting-piece B, so as to change the length of the strap on either side of the body to compensate for any side-wise movement thereof.

My first improvement relates to the construction of the clamp C, its hook D, and the buckle E, with which it coöperates. As will be best seen from Figs. 5 and 6, the clamp C consists of the main body plate, in which is pivoted the clamping-jaw H, which is L-shaped in vertical section, as shown in Fig. 6, and which is adapted when brought into the position shown in Fig. 6 to securely fasten the outer end of the main strap A, forming the loop F, to said clamp. The buckle E consists of the upper, middle, and lower cross-pieces J, K, and L, connected by the customary side bars. These cross-pieces, necessarily the lower one, and preferably the others, have their edges turned in, as best shown in cross-section in Fig. 6, so as to form a kind of a channel out of each cross-bar, and the hook D instead of having a long hooked portion has a comparatively short one that just fits over the upper edge of the lower cross-piece L, so that when the clamp C is accidentally turned up, as to the dotted-line position in Fig. 6, the hook D will catch over the flange on the cross-piece and engage it, while at the same time turning freely on it like a pivot. By this construction it will be readily seen that I absolutely prevent the hook being disengaged from the buckle, except intentionally by a direct upward thrust on the hook, a movement which does not ordinarily occur accidentally.

Another feature of my invention is the dispensing with the prongs upon the buckle E, as I find that with the construction employed in which the main strap A is passed through the buckle, as clearly shown in Fig. 5, and the tension on the strap is applied to the bottom of the loop F the harder the pull upon the strap the greater the amount of friction between the strap and the buckle, so that the friction alone is sufficient to clamp the buckle tightly upon the strap A against any direct pull at the bottom of the loop, while the buckle will slide freely over the strap if the power is applied directly to the sides of the buckle.

Instead of passing the tabs G directly

through the loop, as shown in my prior patent, I prefer to use a metallic link M, which is shown in cross-section in Fig. 7, and, as will be seen, it consists of two halves of symmetrical shape stamped up and fastened together, as by the rivets N. Each half consists of the rectangular upper loop portion O and the curved channeled portion P, the two channelled portions P when brought together forming a tube, through which the tab G slides freely. To conveniently secure drawers-supporters of any desired form to the link M, I also form on each half the cross-piece Q, the two cross-pieces together forming the bar 15 on which the drawers-supporter can be suspended. I may, if desired, form a projection R at each end of one of the upper sides of the link K to loop over the other half, and thus serve to hold the parts together. This 20 construction, however, is not essential. The rear tab S is constructed like the front tabs and is supported by a link M, similar to the other links, from the loop S', which is preferably formed of an elastic strap and is supported from the rear connecting-piece B in 25 the following manner: The rear connecting-piece, which is best shown in Figs. 2 to 4, consists of the back piece T, which has the flanges U turned out at its sides and provided with lugs, in which is secured the pin V, upon 30 which are mounted the double antifriction-rollers W, over which the strap A slides. These antifriction-rollers W are made double, so that as the stress is applied to one side 35 of the strap the roller on that side can move before the roller on the other side starts to move, and thus the strain will be applied more uniformly. I preferably form at the outer ends of these rollers W the flanges X, 40 which serve to confine the strap A in place and prevent its wearing against the flanges. Pivotally mounted in lugs formed in the lower end of the flanges U is the clamp Y, which is of the customary L shape in cross-section and 45 has the jaws Z coöperating with the ends of the strap S' which pass up into the connecting-piece B, as clearly shown in Fig. 2. The position of the ends of this loop formed by the strap S' is conveniently determined by pushing 50 them up so as to take against the lug A', which is conveniently stamped out of the back piece T, as clearly shown in Figs. 2 to 4. Upon this lug A', I form as a continuation thereof the smaller lug B', which is curved up 55 slightly and serves to coöperate as a spring-catch with the lug C', which is stamped out of the body of the clamp Y, as clearly shown in Figs. 2 and 4. By employing this construction when the clamp Y is thrown into place 60 the catch C', taking over the catch B', serves to hold the clamp Y against any accidental movement, while yielding readily to any intentional pull thereon to release the loop S'.

In case I desire to employ a rear tab, consisting of a strap suspended directly from the connecting-piece B—as shown in my prior

patent, No. 638,428, above referred to—I may form another pair of lugs on the flanges U, in which is secured a circular cross-piece D', which might be provided with an antifriction-roller, and over which the strap forming the rear tab will pass. In case this construction is employed the clamp Y might be constructed with a smooth jaw instead of a toothed one, as there will be very little strain upon the 75 jaw and the smooth jaw will permit the necessary adjustment of the strap constituting the tabs.

While I have shown my invention as embodied in the form which I at present consider best adapted for carrying out its purposes, it will be understood that it is capable of some modification and that I do not desire to be limited in the interpretation of the following claims save as may be necessitated by 80 the state of the art.

What I claim as new, and desire to secure by Letters Patent of the United States, is—

1. In a device of the class described, the combination with the main strap having the hook C secured to its end, the hook portion D thereof being short as shown, of the buckle E adjustable on said strap and having its lower cross-piece L formed with the rearwardly-projecting upper edge so as to engage 90 with said hook portion D and prevent its displacement, and the tab supported by the loop formed by engaging the hook C with the buckle E, substantially as shown and described.

2. In a device of the class described, the combination of the main strap having the buckle E formed with the cross-pieces J, K and L slidingly mounted thereon, and the hook C secured to the lower end thereof and adapted to take over the cross-piece L to form a loop, 100 with the tab G supported from said loop by a link M consisting of the two symmetrical halves secured together so as to form the link-body proper rigidly supporting the tube P through which the tab slides, substantially 105 as shown and described.

3. In a device of the class described, the combination of the main strap having the buckle E formed with the cross-pieces J, K and L slidingly mounted thereon, and the hook C 115 secured to the lower end thereof and adapted to take over the cross-piece L to form a loop, with the tab G supported from said loop by a link M consisting of the two symmetrical halves secured together so as to form the link-body proper rigidly supporting the tube P 120 through which the tab slides and having the cross-pieces Q thereon, substantially as shown and described.

4. In a device of the class described, the 125 combination with the main strap having the hook C secured to its end, the hook portion D thereof being short as shown and the buckle E formed with the cross-pieces J, K and L slidingly secured thereon, the lower cross-piece I being formed with the rearwardly-projecting upper edge so as to engage with said 130

hooked portion D and preventing its displacement when engaged therewith to form the loop F, of the tab G supported from said loop.

5. In a device of the class described, the combination with the main strap having the hook C secured to its end, the hook portion D thereof being short as shown and the buckle E formed with the cross-pieces J, K and L slidingly secured thereon, the lower cross-piece L being formed with the rearwardly-projecting upper edge so as to engage with said hooked portion D and prevent its displacement when engaged therewith to form the loop F, of the tab G supported from said loop

15 by a link M consisting of the two symmetrical halves secured together to form an aperture through which the loop passes and the curved tube P through which the tab slides, substantially as shown and described.

20 6. In a device of the class described, the combination with the strap A carrying the tabs at its ends, of the back piece B carrying the roller W over which said strap slides and having the clamp Y beneath said roller, and

25 the loop S' formed by a strap having its ends secured in the piece B by said clamp and supporting the rear tab.

7. In a device of the class described, the combination with the strap A carrying the tabs at its end, of the back piece B carrying the roller W over which said strap slides and having the clamp Y beneath said roller, and the rear tab comprising a strap held in place by said clamp.

30 35 8. In a device of the class described, the combination with the strap A carrying the tab at its ends, of the back piece B carrying the rollers W provided with the flanges X over which said strap slides and having the

clamp Y beneath said rollers, and the loop S' 40 formed by a strap having its ends secured in the said clamp and supporting a rear tab.

9. In a device of the class described, the combination with the strap A carrying the tabs at its ends, of the back piece B carrying 45 the roller W over which said strap slides and having the clamp Y beneath said roller and the projection A', and a back piece comprising a strap S' secured in said back piece by the clamp Y and having its position adjusted 50 by the projection A', substantially as and for the purpose described.

10. In a device of the class described, the combination with the strap A carrying the tabs at its ends, of the back piece B carrying 55 the cross-piece over which said strap slides and having the clamp Y secured thereto beneath said cross-piece provided with the catch-lug C', and the projection A' projecting inwardly therefrom and provided with the lug 6c B', and the loop S' adapted to be engaged by the clamp Y.

11. In a device of the class described, the combination with the strap A carrying the tabs at its ends, of the back piece B carrying 65 the cross-piece over which said strap slides and having the clamp Y beneath said cross-piece provided with the catch-lug C', the projection A' in said back piece terminating in the lug B' adapted to coöperate with the 70 catch-lug C', and the loop S formed by a strap having its ends secured in said clamp and positioned by the lug A', substantially as and for the purpose described.
